MASONRY SAW

Neligh Clair Coates, Kansas City, Mo., assignor to
 Clipper Manufacturing Company, Kansas City,
 Mo., a corporation of Missouri

Application October 26, 1946, Serial No. 705,825

11 Claims. (Cl. 125—13)

1

This invention relates in general to masonry saws and it refers more particularly to improvements in the apparatus and system for supplying lubricant to the disk cutter in such saws.

Masonry saws are of course well-known, being employed in practice to cut stone, bricks, tiles, and the like to the shapes and sizes needed, for instance in building construction and furnace building. The cutting is performed by a disk-like tool rotated at high speed, the tool being formed of an abrasive such as Carborundum or steel alloy rimmed with diamond dust. It usually is desirable to supply a lubricant to the rim of the disk where it engages the workpiece, and in the past it has been customary to jet the lubricating fluid against the sides of the disk so that it is carried to the rim by centrifugal force. Due to the rough texture of the side walls however this method of application has entailed considerable splattering, and it also has been characterized by rather uneven distribution of the lubricating fluid around the disk.

It is an object of the invention therefore to provide an improved method and apparatus for applying lubricant to the cutter disk whereby these difficulties are overcome.

Another object is to provide apparatus for jetting a lubricant toward the cutter from opposite sides, together with facilities for easily removing the fluid connections from their support.

Another object is to provide an improved lubricant circulating system and more particularly a system which will function automatically, without priming, whenever the saw is started.

Another object is to provide a self-priming arrangement for a pump situated above the level of the liquid to be pumped.

Another object is to provide an improved valve arrangement for minimizing the need of priming a pump situated above the level of the liquid to be pumped.

Another object is to provide an improved pump and also to provide an improved arrangement for driving the pump and the cutter disk of a masonry saw from a common pulley.

Another object is to provide in a lubricant circulating system for a masonry saw, an improved pump intake.

Other and further objects will appear in the course of the following description of the invention.

In the accompanying drawings which form a part of the specification and are to be read in conjunction therewith and in which like ref-

erence numerals are employed to indicate like parts of the various views:

Fig. 1 is a side elevation of a masonry saw embodying the invention, part being broken away for purposes of illustration.

Fig. 2 is an elevational view showing the opposite side of the upper portion of the saw.

Fig. 3 is a plan view of the lubricant-circulating pump for the saw, shown to an enlarged scale.

Fig. 4 is a sectional view taken along the lines 4—4 of Fig. 3 in the direction of the arrows.

Fig. 5 is a view taken along the line 5—5 of Fig. 3 in the direction of the arrows.

Fig. 6 is an enlarged detail view of the pulley and belt arrangement for driving the saw and the pump.

Fig. 7 is a sectional view taken along the line 7—7 of Fig. 6 in the direction of the arrows.

Fig. 8 is an enlarged sectional view taken along the line 8—8 of Fig. 1 in the direction of the arrows.

Fig. 9 is a sectional view taken along the line 9—9 of Fig. 8 in the direction of the arrows.

Fig. 10 is an enlarged sectional view taken along the line 10—10 of Fig. 1 in the direction of the arrows.

Referring more particularly to the drawings, the frame or standard of the saw comprises a pair of front legs 11, a pair of rear legs or uprights 12 and a horizontal bed 13 which takes the form of a tray or reservoir. Above the tray is a cutter head; this comprises a deck or platform 14 having an electrical motor 15 mounted on the rear end thereof and an abrasive cutting disk 16 mounted in suitable bearings at the forward end. The cutter head is carried by pins 17 extending laterally of the platform 14 into oppositely disposed ones of the notches 18 provided in the rear uprights.

To prevent the platform from rocking about these pins when the saw is in use, a generally vertical rod 19 which is pivotally attached at its upper end to the rear of platform is clamped rigidly at its lower end by means of a pair of dogs (not shown) which are controlled by the horizontal tube 21 and the manual adjustment knob 22. The grip of the dogs on the rod 19 may be loosened by turning the knob, whereby platform 14 then may be rocked about pin 17 to raise or lower the cutting disk at will.

Wings 23 are provided on opposite sides of the rod 19 so that a pin may be threaded through one of the holes 24 in the rod and rested on the top surface of the wings to facilitate transferring pivot pins 17 from a lower set of notches

18 to a higher set, or vice versa. The apparatus and method for adjusting the height of the cutter head is described more in detail in my co-pending application, Serial No. 584,544, filed March 24, 1945, which issued as Patent No. 2,450,371, dated September 28, 1948, and forms no part of the present invention.

Mounted on the platform 14 between the motor and the cutting disk is a lubricant-circulating pump 26. It is driven by the motor through a narrow V-belt 27 mounted on the motor pulley 28 in the manner best seen in Figs. 6 and 7. A wider V-belt 29 aligned with the narrow belt 27 and operating directly over the narrow belt in a wider part of the motor pulley drives the cutting disk 16. A screen guard 30 secured to the platform covers both belts.

The pump draws lubricant from the reservoir 13 through an intake valve 33, which will be described in more detail presently, thence through the flexible hose 34 and discharges it through hose 35 into a manifold 36. Mounted on top of the guard 37 which covers the upper portion of the cutting disk, this manifold has a pair of tubes 38 extending obliquely downward inside the guard and terminating in small apertures through which the lubricant is jetted toward opposite faces of the disk or, more specifically, toward the hub plates 42 between which the disk is clamped. The tubes 38 are slidably supported in sleeve-like sheathes 40 which are welded or otherwise rigidly affixed to the inner vertical walls of the guard 37 so that by merely removing the screws 41 which fasten the manifold to the guard the manifold and its attached tubes may be withdrawn from the supporting sheathes 40. Small screws 39 provided in the ends of the tubes are removable to facilitate the cleaning thereof.

Since the abrasive cutting disk rotates at high speed the lubricant jetted against the sides of the hub plates 42 is carried outwardly by centrifugal force, first over the curved marginal edge of the hub plates and then along the opposite faces of the disk in the form of a thin film until it reaches the periphery of the disk where the cutting occurs. In the past it has been the practice to jet the lubricant directly against the roughened surface of the abrasive disk, but this is quite unsatisfactory because the strong air currents which are set up by the roughened sides intercept and otherwise interfere with the jet, spattering it over a wide area; also, great pump pressure is required in order to make the lubricant penetrate this zone of fast moving air and reach the surface of the disk. I have found that by directing the jets against the smooth surface of the plates 42 where these strong air currents do not exist, and permitting the lubricant to flow over the curved edges thereof onto the disk, less pump pressure is required, and an excellent distribution of fluid is obtained with substantially no spattering.

A trough 43 is removably attached to the forward edge of the guard by means of a U-shaped spring clip 44 having inturned ends which fit into registering holes in the trough and guard. This trough has inwardly projecting upturned edges which form a gutter between the guard and the sides of the cutting wheel for collecting excess lubricant and draining it back through spout 43a onto the wheel near the center thereof. Thus the excess fluid is recirculated to supplement the lubricant supplied by the jets.

Beneath the cutting wheel is a workpiece con-

veyor or carriage 45. This carriage has flanged wheels 46 operating in roller bearings, which wheels roll upon the upper rim of the tray 13 and permit the carriage with the stone, brick or tile workpiece positioned thereon to be moved back and forth beneath the cutting wheel. The cutting wheel turns in the direction indicated by the arrows in Figs. 1 and 2, and lubricant thrown rearwardly from the lower edge thereof is drained back into the reservoir by a curtain and splash board (not shown) located between the rear uprights 12.

Turning now to Figs. 3, 4 and 5 the construction of the pump will be described in detail. It comprises a casing 26 having therein a vertical partition 47 on one side of which is a large chamber 48. Communicating with this chamber (which hereinafter will be referred to as the suction chamber) is the pump intake 49.

On the opposite side of the partition there is, at best seen in Figs. 4 and 5, a lower chamber housing the impeller 50 and an upper chamber 51 which hereinafter will be referred to as the pressure chamber. An aperture 52 (Fig. 5) connects the latter two chambers, and a removable cover 53 gives access to them, this cover having near its bottom a plug 54 which is removable for the purpose of draining the pump, and having at the top a discharge port 55 which communicates with the pressure chamber.

The partition 47 has two openings therethrough, a small one (56) near the top and a larger one (57) which encircles the hub of the impeller 50. The impeller is rigidly secured to a shaft 58 having the pulley 59 affixed to the other end thereof. This shaft is rotatably supported by a bearing 61 mounted in the pump casing as shown in Fig. 4, and it is encircled by a suitable fluid sealing ring 62.

An opening is provided in the top of the large chamber 48 so that the pump may be filled with lubricant like that in reservoir 13 when the masonry saw is originally placed in service. Filler cap 63 then is screwed into place in the opening and it ordinarily is unnecessary to again fill the pump in the course of normal usage, even though such use is intermittent, unless it is intentionally emptied.

In operation, the impeller is driven by motor 15 in the direction indicated by the arrow (Fig. 5) whereupon it draws fluid from the suction chamber 48 through aperture 57 and expels it through aperture 52 into the pressure chamber 51. Due to the suction thus created on the inlet side of the impeller chamber, fluid is drawn from the reservoir 13 through hose 34 and inlet port 49 into the suction chamber to replace that expelled into the pressure chamber. From the pressure chamber most of the fluid is driven through the outlet port 55, hose 35, manifold 36, and tubes 38 from which it is jetted against the sides of the rotating hub plates; however, part of the fluid forced into the pressure chamber flows back into the suction chamber through aperture 56. This serves the important function of priming the pump at the beginning of its operation.

More specifically, in the brief period during which the impeller is accelerating from a standstill it is unable, because of its low speed and also because of the fact that a certain amount of air may be trapped in the hose 34, to draw sufficient liquid into the suction chamber from the reservoir 13 to replace all that which leaves the suction chamber through orifice 57. Were the suction chamber to "go dry" the pump naturally would

be in danger of becoming inoperative and accordingly the recirculation of fluid from the pressure chamber to the suction chamber is important in overcoming this danger. The recirculation continues to a certain extent throughout the operation of the pump but at full speed the greatest part of the work done by the pump is useful, i. e., drawing fluid in through port 49 and expelling it through port 55.

Fig. 10 shows in detail the construction of the intake valve through which the pump draws lubricant from the reservoir 13. It comprises a cylindrical shell 33 having a deep socket-like recess or lower chamber 65 and an upper chamber 66 connected thereto by a small orifice 61. A small steel ball 68 rests in a tapered socket at the bottom of the upper chamber and spaced above the ball a short distance is a pin 69 extending diametrically across the chamber with its ends rigidly affixed in registering holes in the opposite walls. A nipple 70 is screwed into the upper chamber above the pin to permit the hose 34 to be connected thereto.

The valve 33 is maintained erect on the bottom of the tray 13 by means of a rigid stud 72 over which the recess or socket 65 fits. When the pump is operating fluid enters the lower chamber through the openings 73 covered by screen 74, flows upwardly through orifice 61, around the ball 68 (which now is carried upwardly against pin 69) and out into the hose 34 by way of nipple 70. When the pump ceases to operate there is a tendency for the fluid standing in hose 34 to run back down into the reservoir 13. The ball 68 settles back into its tapered recess to prevent this, however, and thus the level of lubricant is maintained near the pump inlet port. This maintains the air trapped in the hose at a minimum, and hence reduces the tendency of the suction chamber to "go dry" when the pump is again started.

The valve 33 also serves another useful purpose on those occasions when the pump is intentionally drained, for example in freezing weather. To refill the pump, the valve simply is lifted from the supporting stud 72, turned end for end, and held above the pump; when supported thus it serves as a funnel through which lubricant may be poured so that it will run down the hose 34 into the pump. After the pump has been filled, the valve is restored to its normal position on stud 72 and the same used as previously described.

From the foregoing it will be seen that my improved lubricating system and apparatus are well adapted to attain all of the ends and objects hereinbefore set forth together with other advantages which are obvious and which are inherent to the apparatus.

It will be understood that certain features and subcombinations are of utility and may be employed without reference to other features and subcombinations. This is contemplated by and is within the scope of the claims.

Inasmuch as many possible embodiments of the invention may be made without departing from the scope thereof it is to be understood that all matter herein set forth or shown in the accompanying drawings is to be interpreted as illustrative and not in a limiting sense.

Having thus described my invention, I claim:

1. In a masonry saw, an abrasive cutting disk, a relatively smooth hub plate adjacent one side of the disk and covering the center portion of the rough side wall of said disk, means for rotating the disk and the hub plate as a unit, a nozzle

spaced laterally from the exposed face of said plate, means for jetting a lubricant through said nozzle onto the rotating hub plate, said hub having a thin marginal edge contacting the rough side of the wall of the disk and having a thicker central portion, the exposed face of the plate tapering smoothly from the central portion toward the edge whereby the lubricant on the plate flows by centrifugal action over the thin edge of the plate onto the rough side wall of the disk.

2. A masonry saw as claimed in claim 1 where-in said lubricating fluid is jetted on said plate substantially normal to the plane of the cutter.

3. A masonry saw comprising a cutter head, a disk-like cutter rotatably mounted on the head, a guard carried by the head and surrounding the upper part of the cutter, a pair of parallel sleeves rigidly affixed to said guard on opposite sides of said cutter, fluid connections for jetting a lubricant against opposite sides of the cutter, said connections including a manifold having a pair of parallel tubes rigidly connected thereto, said tubes removably insertable in said sleeves for support.

4. In a masonry saw, a rotating cutter disk, a tray below the disk, a lubricant for the disk contained in the tray, means including a pump operative to draw lubricant from the tray and introduce it on the disk, said pump having a flexible intake line terminating in a funnel-like member normally occupying an inverted position with its mouth submerged in the lubricant contained in the tray.

5. In a masonry saw, a rotating cutter disk, a tray below the disk, a lubricant for the disk contained in the tray, means including a pump operative to draw lubricant from the tray and introduce it on the disk, said pump having an intake line whose inlet is submerged in the lubricant contained in the tray, and a check valve in the line substantially at said inlet for preventing the flow of lubricant away from the pump through said line.

6. In a masonry saw, a rotating cutter disk, a tray below the disk, a stud extending vertically upward from the bottom of the tray, lubricant for the disk contained in the tray, means including a pump operative to draw lubricant from the tray and introduce it on the disk, said pump having a flexible intake line terminated by a sleeve adapted to be positioned over said stud so it closely encircles same and is held upright thereby, and apertures in the sides of the sleeve above the stud for admitting the lubricant in the tray to the interior of the sleeve.

7. In a masonry saw, a cutting disk and a motor each having a pulley, a pump having a pulley situated intermediate the motor pulley and the disk pulley, said three pulleys being disposed in a common plane and all having V-shaped belt tracks, a narrow V-belt linking the motor pulley and pump pulley, and a wider V-belt linking the motor pulley and the disk pulley.

8. In a masonry saw, an abrasive cutting disk, a relatively smooth circular hub plate engaging one side of the disk and covering the center portion of the rough side wall of said disk, the periphery of said disk being beveled so it meets said one side of the disk in an obtuse angle, means for rotating said disk and hub plate as a unit, and means spaced from the exposed face of the rotating hub plate for jetting fluid onto said face.

9. In a masonry saw, an abrasive cutting disk having rough side walls each disposed in a flat plane normal to the axis of the disk, a smooth

hub plate adjacent one side of the disk and covering the center portion of the rough side wall of the disk, means for rotating the disk and hub plate as a unit whereby the exposed rough side walls of the disk generate air currents containing such walls, a nozzle spaced laterally from the exposed face of said plate, means for jetting a lubricant through said nozzle onto the rotating hub plate, said hub plate having a thin marginal edge contacting the rough side wall of the disk and having a thicker central portion, the exposed face of the plate tapering smoothly from the central portion toward the edge whereby the lubricant on the plate flows by centrifugal action over the thin edge of the plate onto the rough side wall of the disk underneath said curtain of air currents.

10. In a machine, a driving pulley and a pair of driven pulleys all located in the same plane with one driven pulley disposed between the driving pulley and the other driven pulley, a belt linking the driving pulley and said one driven pulley, and a second belt over-laying the first

belt and linking the driving pulley with said other driven pulley.

11. A machine as in claim 10 wherein said one driven pulley is smaller in diameter than said other driven pulley.
